HAIR CURLER AND CLIP ASSEMBLY

Everald J. Saucier, Hartford, Conn.

Application October 18, 1946, Serial No. 704,142

7 Claims. (Cl. 132—33)

1

This invention relates to the art of hair dressing, and an object of the invention is to provide an efficient device for use in forming spiral curls or ringlets which lie flat against the scalp.

The present application is a continuation-in-part of an application for patent filed by me on June 5, 1946, Serial Number 674,496, and entitled "Hair curler."

Among the objects of the present invention is to provide certain new and useful improvements over that type of curler described and claimed in my aforementioned co-pending application, and more specifically to provide a hair curler characterized by an actuating rod and a hair winding spool that so complement one another as to facilitate the winding of the hair on the spool for the full length of the strand of hair being curled.

Further, in accordance with the present invention an improved clip to facilitate removal of the curled hair from the spool and the retaining of the hair in curled condition on the head is provided.

The present invention, together with its objects and advantages will be best understood from the following detailed description when read in reference to the accompanying drawings in which is illustrated a preferred embodiment of the invention, and wherein:

Figure 1 is a perspective view illustrating the application of a hair curler embodying the features of the present invention;

Figure 2 is a plan view of the curler;

Figures 3, 4 and 5 are detail sectional views taken substantially on the lines 3—3, 4—4 and 5—5 respectively of Figure 2;

Figure 6 is a plan view of one part of a two-part clamp forming part of this invention;

Figure 7 is a view similar to Figure 6 of the second part of the two-part clamp;

Figure 8 is an elevational view taken substantially at right angles to Figure 6 and looking in the direction of the arrow;

Figure 9 is an elevational view taken at right angles to Figure 7 and also looking in the direction of the arrow of Figure 6; and

Figure 10 is a side elevational view of the spool and clip showing the parts assembled, preparatory to removing the curled hair from the spool.

Referring more in detail to the drawings, it will be seen that generally the hair curler or winding device as contemplated by the present invention comprises an actuating shaft 5 and a spool 6, the latter being adapted to have a tress of hair wound thereon.

2

The spool 6 is somewhat similar to that shown and described in my hereinbefore identified co-pending application. The body of the spool is provided with a frusto-conical end portion 7 and an end portion 8 which latter is substantially of uniform diameter throughout its length. At the junction of the portions 7 and 8, the spool is provided with a flange 9 that provides an end head for the portion 7 of the spool.

10 The frusto-conical portion 7 of the spool constitutes the barrel section upon which the strand of hair to be curled is wound. For securing the tip end of the strand or tress to the barrel portion 7, there is provided a clip indicated generally by the reference numeral 10.

Similar to the clip described in my aforementioned co-pending application, clip 10 embodies a jaw portion 11 that overlies the frusto-conical portion 7 of the spool and is adapted to be flexed into and out of clamping position with respect thereto.

20 The jaw 11 is formed integral with a hand lever 12 that extends in divergent relationship with respect to a lever 13 that is formed integral with, and is joined to the jaw 11 and hand lever 12 at the junction of said jaw and lever through the medium of a web 14.

25 The clip 10 is disposed on the spool 6 in the manner shown to advantage in Figure 3. As therein illustrated, the levers 12 and 13 are disposed at one side of the flange 9 while the jaw 11 is disposed at the opposite side of the flange in operative position to the barrel portion 7 and has a working fit in a slot 15 formed therefor in the flange 9. Also, the barrel section 7 is provided on its periphery with a longitudinal groove 16 in which the jaw 11 fits.

30 From the foregoing it will be seen that by exerting pressure on lever 12 in the direction of the lever 13, jaw 11 will be flexed away from the barrel section 7 so as to receive between jaw 11 and the grooved portion of the barrel 7, the free end or tip of the strand of hair, preparatory to rotation of the spool on the actuating shaft 5 for effecting a winding of the hair on the spool, incidental to forming the curl.

35 The actuating shaft 5 is provided with a pair of intersecting right and left-hand threads or spiral grooves as at 17 connected at their opposite ends as at 18 to be alternately engaged by an internally projecting key or pin 19 carried by the spool 6. Thus it will be seen that by exerting a pull on the spool 6 relative to the actuating shaft 5, the spool 6 will be caused to rotate about the shaft 5 as an axis as it moves longitudinally

along the actuating shaft. This rotative movement of the spool will result in a winding of the hair on the spool for forming a curl.

To facilitate proper manipulation of the spool 6, the latter is provided at the free end of the barrel portion 8 thereof with a knurled knob 20. This knob 20 is in the form of an annulus sleeved on the terminal of the barrel part 8 and releasably retained thereon against axial displacement through the medium of a pin 21 that is passed through aligned openings provided therefor in the knob and engages in a peripheral groove 22 provided therefor in the barrel section 8, as shown to advantage in Figures 3 and 4. It will thus be seen that the spool 6 is free to rotate relative to the knob 20, while at the same time the knob 20 provides a convenient handhold for proper manipulation of the spool.

The actuating shaft 5 is also provided at one end with a reduced portion on which is sleeved a knurled knob or fingerhold 23. As shown to advantage in Figure 5, knob 23 is also provided with a retaining pin 24 which engages in a peripheral groove 25 provided on the reduced end 26 of shaft 5. Thus it will be seen that shaft 5 is free to rotate relative to knob 23 as conditions of use, hereinafter pointed out, will require.

In using the hair curler or winder structure as just described, a strand of hair is drawn outwardly from the head of the user as suggested in Figure 1 and the tip end of the tress is placed upon the spool section 7 and clamped thereon in an obvious manner by the action of the clamping jaw 11. At the time of initially engaging the strand of hair with the spool 6, the latter is at the extreme end of shaft 5 remote from knob 23.

After the tip end of the strand has been secured in position on the spool 6, the operator with one hand grasping the knob 20 of the spool, and the other hand grasping the knob-equipped end 23 of shaft 5, exerts a pull on the spool 6 in direction of the last mentioned end of the actuating shaft. This will cause spool 6 to move lengthwise of shaft 5 and at the same time rotate about the shaft 5 as an axis and in a direction to cause the strand of hair to wind on the spool.

In the event that at the time the spool 6 reaches end 23 of shaft 5, the strand of hair has not been completely wound upon spool 6, the operator then exerts a pull on shaft 5, holding the spool 6 against rotation. This action will result in a feeding of the shaft 5 axially through the barrel of the spool 6 in a direction for again placing the spool at the end of the shaft 5 farthest remote from the knob 23, or in other words in again locating the spool 6 at that position on the shaft 5 shown in Figure 2. The parts are now in a position which will permit of a repetition of the operation hereinabove first described for effecting a continuing of the winding of the hair upon the spool until all, or substantially all, of the tress is wound thereon.

For compressing and removing the coil of hair from the spool 6 and also to prevent unrolling and to hold the curl flat against the scalp, there is provided a two-part clamp indicated generally by reference numeral 27.

The clamp 27, as shown to advantage in Figures 6 to 9 inclusive, comprises a female section 28 and a male section 29, each being of substantially inverted L-shape.

The clamp member 28 has a vertical arm 30 bifurcated as at 31 to straddle the spool 6, and a horizontal arm 32 embodying upper and lower

parallel portions forming therebetween a socket 33 having a longitudinal slot 34 in the top wall thereof.

The male member 29 of the clamp has a vertical arm 35 provided with teeth 36 and a horizontal arm 37. The latter arm is adapted to be slidably associated with the socket 33 and is provided on its upper surface with a longitudinal rib 40 that has a working fit in the slot 34 to retain the assembled sections against lateral displacement relative to one another.

For securing the members 28 and 29 of the clamp, when assembled, and at the desired adjustment relative to one another the arm 37 of member 29 has its laterally enlarged portion provided on opposite edges with saw teeth 41 with which are engageable detents 42 with which the clamp member 28 is equipped.

The detents 42 are in the form of levers formed integral with the member 28 and disposed at opposite edges of the horizontal arm of said member. The lever portions of the detents 42 are provided with integral handles 43 whereby the detents may be readily flexed out of engagement with the toothed or serrated edges 41 to permit ready adjustment of the clamp members.

In using the clamp, the arm 30 of clamp member 28 is placed in a position straddling the portion 7 of spool 6, the legs of the furcation 31 passing between the flange 9 and the hair coil as shown in Figure 10. Next, the clamp member 27 has its arm 31 inserted in the socket 33 and moved inwardly thereof until the arm 35 of member 29 bears against the free end of the spool section 7 as also shown in Figure 10. Clamp member 28 is then moved lengthwise of the spool in the direction of the clamp member 29 to substantially the dotted line position shown in Figure 10 to thereby effect a compressing of the coil between the arms 30, 35 of the clamp. The clamp members are secured in this coil-compressing position by reason of engagement of the detents 42 with the teeth 41. With the parts and position just described, the clamp is bodily moved in an obvious direction for effecting removal of the coil of hair from the spool 6 and a complete disassociation of the clamp and spool.

From the foregoing, it will also be apparent that with the teeth 36 of clamp member 29 engaging the hair in the proximity of the scalp, the clamp will serve to retain the coil compressed and also snugly against the head of the patron.

It will be understood that the several parts of the curler and of the clamp may be produced from any of a number of materials including metal and plastics, it being understood that the material used for the clamp is preferably of a resilient nature so that the necessary flexing thereof may be effected manually and without danger of damage thereto.

It will be further understood that the device of my invention is adapted for use both in permanent waving and in hand setting the hair.

While a specific form of my invention has been described and illustrated herein, it will be understood that the same may be varied without departing from the spirit of the invention or the scope of the claims hereto appended.

What I claim is:

1. A hair ringlet curler comprising a spool for receiving a coil of hair, an actuating shaft for the spool, and a clamp assembly for compressing and removing the coil of hair from the spool and for holding the coil flat against the scalp having a part formed to straddle the spool at one end

of the coil of hair and initiate engagement of the clamp with the coil.

2. In a hair winding device, a spool for receiving a coil of hair, an actuating shaft for the spool, and interengaging means on the spool and on the actuating shaft for imparting relative rotative movement to the spool about the shaft as an axis.

3. In a hair winding device, an actuating shaft provided with intersecting right and left hand spiral grooves, and a spool adapted to have a tress of hair wound thereon provided with a key having working engagement with the grooves of said shaft.

4. A hair ringlet curler comprising an actuating shaft provided with intersecting right and left hand spiral grooves, a knob rotatably mounted on one end of the shaft, a spool for receiving a coil of hair provided with an internal key having working engagement with the grooves of said shaft, and a knob rotatably mounted on one end of the barrel of the spool.

5. In a hair winding device, a spool for receiving a coil of hair, an actuating shaft for the spool, inter-engaging means on the spool and on the shaft for imparting relative rotative movement to the spool about the shaft as an axis, and a clamping jaw mounted on the spool and co-operable with the barrel of the latter for clamping the tip end of the tress of hair to the spool.

6. In a hair ringlet curler a spool upon which a tress may be wound to form a ringlet, and a clamp for compressing and removing the coil of hair from the spool and to hold the curl flat against the scalp comprising a pair of complementary members one of which is provided for straddling the spool to initially engage the clamp with the coil and the other of which is provided for engaging the hair in proximity to the scalp.

10 7. In a hair ringlet curler a spool upon which a tress may be wound to form a ringlet, a clamp for compressing and removing the coil of hair from the spool and to hold the curl flat against the scalp comprising a pair of complementary members one of which is provided for straddling the spool to initially engage the clamp with the coil and the other of which is provided for engaging the hair in proximity to the scalp, and inter-engaging means on the complementary clamp members for releasably securing the same in adjusted clamping position.
